UNITED STATES PATENT OFFICE.

JOSEPH BANOVITCH, SR., AND JOSEPH BANOVITCH, JR., OF CARTERSVILLE, VIRGINIA.

TOY.

1,127,388.

Specification of Letters Patent.

Patented Feb. 9, 1915.

Application filed June 2, 1914. Serial No. 842,466.

To all whom it may concern:

Be it known that we, JOSEPH BANOVITCH, Sr., and JOSEPH BANOVITCH, Jr., citizens of the United States, residing at Cartersville, 5 in the county of Cumberland and State of Virginia, have invented new and useful Improvements in Toys, of which the following is a specification:

An object of the invention is to provide 10 a toy which consists of few parts and can be cheaply manufactured, the toy, among other features, contemplating gravitationally movable parts which will afford great amusement, and which, when once set in motion, 15 will continue to operate for a considerable period of time due to the counterbalancing of the parts which coöperate to produce the desired result. To this end use is made of a counterbalancing element suitably supported to swing on a support, with 20 the element having one or a plurality of movable parts or portions which, in the operation of the counterbalancing element, will be correspondingly operated to produce 25 a unique and novel effect.

In the further disclosure of the invention reference is to be had to the accompanying drawings, constituting a part of this specification, in which similar characters of reference denote corresponding parts in all the 30 views, and in which:

Figure 1 is a side elevation of the toy, showing one of the movable parts of the counterbalanced element, portions of which 35 are broken away to disclose the underlying structure; Fig. 2 is a similar view showing another part of the counterbalanced element made movable, parts being broken away to disclose the underlying structure; Fig. 3 40 is a similar view showing still another part of the counterbalanced element made movable, parts being broken away to disclose the underlying structure; and Fig. 4 is a similar view showing still another part of 45 the counterbalanced element made movable, parts being broken away to disclose the underlying structure.

Referring more particularly to the views, we provide a counterbalanced element 10 arranged upon a suitable support 11, the 50 said counterbalanced element 10 consisting, more particularly, of a body 12 which may be of any desired shape or representation and in this instance is shown to represent

a cavalryman, depicting the same seated on 55 a horse. The body 12 has a stem 13 projecting from its under side and curved rearwardly from the body, with the stem 13 terminating at its free end in a suitable weight 14, and portions 15 of the body, 60 and which, in Fig. 1, are shown to be the hind legs of the horse, have suitable pins 15 and 16 projecting therefrom, and which are provided to swingingly support the body 65 upon the support 11.

A movable member 17 is arranged to swing on the body, said movable member having a suitable weight 18 forming a part thereof and preferably arranged to swing with the movable member, the said weight, 70 however, being disposed inside of the body so as not to be visible from the exterior thereof. An operating member 19 which, in this instance is shown to be a cord, is arranged on the counterbalanced element 10 75 and has one end thereof connected with the stem 13 below the horizontal plane of support of the body and the other end thereof connected with the movable member 17 arranged above the plane of support of the 80 body. In Fig. 1 the movable member is represented as the tail of the horse and the tail is connected with the cord 19 as mentioned and which has connection with the stem 13, a suitable eye 20 being formed 85 on the stem to provide the connection.

Now it will be apparent that when the counterbalanced element 10 is arranged upon the support 11 and a forward and backward swinging movement is imparted 90 thereto, the weight 14 on the lower end of the stem will cause the movement to be continued for a considerable length of time, said weight acting as a counterbalance for the body 12. As the counterbalanced ele- 95 ment swings back and forth, however, a portion of the cord between its ends will engage the support 11 and thus swing the movable member 17 against the gravitational action of the weight 18 so that when 100 the cord is disengaged from the support upon a subsequent downward movement of the forward part of the body, the movable member will assume its normal position due to the weight. Thus it will be apparent 105 that each time the body swings upwardly or, as might be stated, when the horse assumes a position as if it were standing on its hind

legs only, the tail of the horse will be operated by the action of the cord engaging the support and the tail will be returned to normal position upon the downward swinging movement of the horse or body.

In Fig. 2 we disclose substantially the same construction except that in this instance the movable member is represented as being the figure of a man and is indicated by the numeral 21, said movable member in this instance having the cord 19 attached thereto, with the cord operating over a suitable pulley or roller 22 on the body. It will of course be understood that the roller or pulley can be dispensed with and that the cord can enter the body through a hole therein for the purpose of attaching the upper end of the cord to the movable member as is here shown as the figure sitting astride of the horse. The weight for the movable member 21 in this instance is indicated by the numeral 23 and is formed to provide the stirrup of the rider.

In Fig. 3, the movable member, indicated by the numeral 24, is shown to be the head of the horse and has the cord 19 attached thereto, and in Fig. 4 the movable member indicated by the numeral 25 is shown to be the fore leg of the horse, it being thus of course understood that both fore legs can be operated at one time by having the cord common to both. In the structure disclosed in Fig. 3 the movable member 24 has a weight 26 similar to the weight shown in Fig. 1 and in Fig. 4 the movable member 25 carries a weight 27 formed to provide the hoof of the fore leg.

In all of the instances shown, however, it will be apparent that the principle is substantially the same and that the object is to provide a counterbalanced member preferably designed in the nature of a toy or grotesque figure and which can be arranged upon a sill or support to swing backwardly and forwardly or upwardly and downwardly and that its upward and downward or backward and forward movement simultaneously operate a movable portion of the member and which has its operation governed by the swinging of the member and by the engagement of a cord or operating mem-

ber with the support on which the body or toy proper is arranged to swing.

Having thus described our invention, we claim:

1. In combination with a support and a counterbalanced element swingingly disposed on the support, a movable member on the element, and means connecting with the movable member and adapted to engage the support to insure the operation of the movable member when the element is operated.

2. In combination with a support and a counterbalanced element swingingly disposed thereon, a movable member on the counterbalanced element, and a cord having a portion thereof adapted to engage the support due to the swinging of the counterbalanced element whereby the operation of the movable member will be insured.

3. In combination with a body, a support, pins projecting from the body for swingingly disposing the body on the support, a stem projecting from the body, a weight on the stem whereby the body will be counterbalanced on the support to swing thereon, a movable member on the body, and means connecting with the movable member and with the stem whereby when the body is operated the said means will contact with the support and cause the operation of the said movable member.

4. In combination with a body, a support, pins projecting from the body for swingingly disposing the body on the support, a stem projecting from the body, a weight on the stem whereby the body will be counterbalanced on the support to swing thereon, a movable member on the body, and a cord connecting with the movable member and with the stem whereby when the body is operated the said means will contact with the support and cause the operation of the said movable member.

In testimony whereof we affix our signatures in presence of two witnesses.
